UNITED STATES PATENT OFFICE.

WILLIAM H. BOTTON, OF CLEVELAND, OHIO, ASSIGNOR TO THE OWEN BUCKET COMPANY, OF CLEVELAND, OHIO, A CORPORATION OF OHIO.

GRAB-BUCKET.

1,223,309.

Specification of Letters Patent. Patented Apr. 17, 1917.

Application filed December 22, 1914. Serial No. 878,630.

To all whom it may concern:

Be it known that I, WILLIAM H. BOTTON, a resident of the United States, residing at Cleveland, in the county of Cuyahoga and

5 State of Ohio, have invented a certain new and useful Improvement in Grab-Buckets, of which the following is a full, clear, and exact description.

This invention relates to grab buckets 10 which are employed for digging and for loading and unloading purposes, and has for its main object to improve the construction, efficiency and durability of buckets of this type.

15 One of the more specific objects is to improve the construction of a bucket head by providing a head composed of a less number of parts than has been required heretofore and which by reason of its construction is 20 durable and not liable to get out of order or interfere with the operation of the bucket and the manipulation of the holding and closing lines. Further the invention aims to provide an improved head which admits 25 of a considerable reduction in the amount of head room required, especially in the distance between the center of the holding sheave and the center of the upper closing block.

30 A still further object is to provide improved means for supporting the bucket jaws by providing bearings which have long life, which can be lubricated without danger of attracting sand and other foreign particles liable to cut the bearings and bushings, and which will prevent the so-called lapping of the jaws and keep the jaw edges in alignment.

The above and other objects are accomplished by my invention which may be 40 briefly summarized as consisting in certain novel details of construction and combinations and arrangements of parts which will be described in the specification and set forth 45 in the appended claims.

In the accompanying sheet of drawings, Figure 1 is a side view of the bucket looking toward one of the jaws, parts being in section; Fig. 2 is a similar view with the bucket 50 turned 90°, parts being in section; Fig. 3 is a perspective view of the bucket head and some of the parts attached thereto; and Fig.

4 is a top plan view of the head with the major portion of the elements which are normally supported thereby removed for the 55 sake of clearness.

Referring now to the drawings, 10 represents the two bucket jaws which are provided with supporting hinges or hinge pieces 11, and the outer portions of which are connected by rods 12 to a head which may be designated as a whole by the reference character 13. This head comprises a single or unitary head piece or body 14 formed in one piece, this member 14 consisting preferably of a steel casting. The head piece is provided with two laterally extending portions 15, each having a pair of downwardly extending ears 16 between which are pivoted by means of pins 17 the upper ends of 70 the arms 12 which extend to the outer four corners of the jaws. The axes of these two pivoting pins 17 which are in alinement as indicated by the line A—A in Fig. 4 will be regarded as the axis of the head piece. Projecting upwardly from the middle portion 75 of the head piece are two integral lugs or plates 18 which receive between them a holding sheave 19 which is rotatably supported between the plates or ears 18 by a pin 20 80 and which receives a holding line 21, one end of which is generally dead ended on a boom, and the other end of which extends to a suitable drum. It will be observed that this sheave is at right angles to the axis of 85 the head piece, and that the axis of the sheave is in the same vertical plane with the axis of the head piece.

Extending downwardly from the head piece and located between the two pairs of 90 ears 16 upon which the arms 12 are pivoted are a series of integral lugs 22 which are arranged in parallel planes at an angle to the axis A—A of the head piece. In this instance I have shown three such lugs 22 95 which receive between them and space apart the sheave plates 23 of the upper closing block 24, the sheave plates being connected to these lugs by a pair of pins or bolts 25 which extend through the sheave plates and 100 through alined openings in the lugs, these bolts and in consequence the axis of the closing block 24, being in this instance at substantially 45° to the axis of the head

piece. This upper closing block 24 is in this instance provided with three sheaves 26 which receive the closing line 27.

The head piece 14 is provided also with an integral lateral extension 14^a projecting outward from one side of the head piece in a general direction at right angles to the axis A—A. This extension, which is provided for the purpose of receiving sheaves and rollers for the closing line, includes a pair of parallel ears 28 which are in planes at right angles to the axis A—A and constitute substantial continuations of the ears 18, 18 which receive and support the holding sheave 19. These ears 28 receive between them and support a pair of lead sheaves 29 for the closing line, these sheaves being mounted upon a pair of pins 30 which extend through alined openings in the ears. The lateral extension of the head piece is provided also with transverse ears or flanges 31 which are parallel to each other and at right angles to the ears 28; these ears or flanges 31 extending between or bridging the vertical ears 28, as shown particularly in Figs. 3 and 4. These ears or flanges 31 receive between them and support a pair of guide rollers 32 for the closing line, these rollers being mounted on pins 32^a which extend into suitable openings 32^b provided in the upper portions of the ears or flanges 31. It will be observed that the transverse ribs or flanges 31 not only support the rollers 32, but constitute strengthening and connecting ribs for the vertical ears 28, thus providing the necessary strength and rigidity to answer all requirements. It will be understood that the ribs 28 and 31 constituting the lateral extension, as above described, are all integral with the head piece 14.

The bucket closing tackle includes in addition to the upper closing block 24 and closing line 27 a lower closing block 33 composed of a plurality of sheaves 34, the number of which is greater by one than the number of sheaves in the upper block. The sheaves of the lower block are spaced apart by a number of sheave plates 35 in which the sheaves 34 are supported by a pin 36 extending through alined openings in the sheave plates 35. The lower block is secured to the upper part of a counterweight 37 (to which the bucket jaws are connected, as will be described), this counterweight having at the top a series of spaced lugs 38 which receive between them and space apart the lower portions of the sheave plates 35 of the closing block 33, these sheave plates 60 being secured to the lugs 38 by a bolt 39 which passes through alined openings in the series of lugs 38 and through alined openings provided in the sheave plates. It will be observed that the lugs 38 are on an angle 65 to the axis of the counterweight and that the

lower block is in consequence skewed or turned with reference to the counterweight axis. The upper and lower closing blocks and the guide sheaves and guide rollers for the closing line are so arranged that, as will be observed particularly from Fig. 1, all parts of the closing cable extending between the sheaves of the upper and lower blocks and between the guide sheaves 29 and one of the end sheaves of the lower block 33 all 70 have clear leads. It will be observed also that both the holding line and that portion of the closing line which extends downwardly through the closing line guide sheaves to the end sheave of the lower closing block are in the center plane of the bucket so that the bucket will stand plumb whether it is supported by the holding line or closing line.

Another important feature of my invention resides in the manner of supporting and pivotally connecting the hinges 11. Heretofore the hinges have been mounted on the ends of a shaft or pin which in a bucket of the counterweight type as here shown extended through the counterweight. That construction, however, had the disadvantage that the bearing surfaces of the hinges were so small that wear necessitated the rather frequent replacement of the 90 hinges. Additionally, it was found difficult to maintain the edges of the jaws in alignment and the lubrication of the bearing surfaces attracted sand which cut the bearing surfaces. These disadvantages are overcome by my invention wherein the means for pivotally connecting the hinges together or to the counterweight 37 consists of two concentric members, namely, a shaft 40 to the ends of which the two hinges extending 100 from one jaw are fastened and a sleeve 41 which is somewhat shorter than the shaft and to the ends of which the other two hinges are fastened. Both the shaft and the sleeve extend through the counterweight, 110 the shaft and sleeve having a suitably close working fit on each other, and the sleeve having a suitably close working fit in the counterweight. The opening in the counterweight is preferably recessed at two 115 points, as shown at 42, this being provided for the purpose of reducing the length of the bearing surface of the sleeve and counterweight and for lubricating purposes. The recesses are preferably filled with a semi-solid lubricating substance, and additionally grease cups 43 may be provided to supply lubricant to these recessed portions. In order that lubricant may find its way from these recesses on to the inner bearing surfaces of the sleeve and shaft, the sleeve is provided with a number of lubricating openings 44.

By fastening the two pairs of hinges rigidly to the two long relatively movable 130

members, one of which has a bearing in the other and both extending through the counterweight very good bearings are provided for these parts throughout the life of the 5 bucket, and there is practically no danger of the bucket jaws lapping or getting out of alinement as was heretofore the case if one corner of the bucket jaws would close on a rock or other hard substance. Additionally, by lubricating the bearing surfaces 10 from what may be termed the interior of the structure, such a small percentage of the lubricant gets on the outer hinging parts that sand and grit will not be attracted to any 15 material extent and cut the bearings.

While I have shown only the preferred construction I do not wish to be confined to the exact details shown, but aim in my 20 claims to cover all modifications which do not involve a departure from the spirit of my invention.

Having thus described my invention, what I claim is:—

1. A head-piece for a grab bucket comprising a central portion provided with laterally extending arms each having downwardly extending ears, and said central portion provided with a pair of upwardly extending ears, and with downwardly extending 25 ears symmetrically arranged with respect to said upwardly extending ears.

2. A head-piece comprising an enlarged central portion provided with laterally extending arms each having downwardly extending ears, and said central portion provided also with upwardly extending ears adapted to support a holding sheave, with downwardly extending ears adapted to support a closing sheave; and with a third set 35 of ears extending laterally from the middle portion said last set of ears being adapted to support guide-members for a closing line.

3. A head-piece for a grab bucket having laterally extending arms each of said arms being provided with a pair of downwardly extending ears, the said pairs of ears being arranged symmetrically with respect to the center of the head; a pair of upwardly extending ears arranged at substantially the 45 center of the head and adapted to support a closing sheave; downwardly projecting ears arranged at substantially the center of the head and adapted to support a closing block; and a pair of laterally extending ears 50 at right angles with respect to the arms for supporting guides for a closing line.

4. A head-piece for a grab bucket having laterally extending arms to which bucket supporting arms are adapted to be connected; a plurality of ears extending downwardly from the head at the central portion thereof, said ears being arranged at an angle 55 with respect to the longest axis of the head; a pair of upwardly extending ears arranged at substantially the center of the head and

adapted to support a holding sheave; and laterally extending ears which are substantially in line with the ears that support the holding sheave, said laterally extending ears adapted to receive a member which guides a 70 closing line.

5. A head-piece for a grab bucket having an enlarged central portion from which extend lateral arms each of said arms being provided with a pair of downwardly extending ears adapted to support bucket arms; a plurality of ears extending downwardly from the enlarged portion of the head, said ears being adapted to support a closing block, the said downwardly extending ears being at an angle with respect to the longest axis of the head. 75

6. A head-piece for a grab bucket having an enlarged central portion; arms extending from the said central portion each of said arms being provided with a pair of downwardly extending ears for supporting bucket arms; a plurality of ears extending downwardly from the enlarged portion of the head, said ears serving to support the 80 closing block; a pair of ears extending upwardly from the enlarged portion of the head said ears serving to support a closing sheave, all said arms and ears being symmetrically arranged with respect to the central vertical axis of the head. 85

7. A head-piece for a grab bucket having an enlarged central portion; arms extending from the said central portion for supporting bucket arms; a means extending downwardly from the enlarged portion of the head and serving to support a closing block; a means extending upwardly from the enlarged portion of the head and serving to support a holding line; and means for supporting guides for a closing line comprising ears extending laterally outward from the central portion and adapted to support guide rollers, and additional ears at right angles to and extending between the first 95 named ears and adapted to support other rollers. 100

8. In a bucket, the combination with

bucket jaws and jaw supporting arms of a bucket head comprising a one-part head-piece having a middle portion; arms projecting laterally outwardly in the direction of the main axis of the head-piece said bucket-supporting arms being connected to said arms of the head-piece; parallel ears 110 extending upwardly from the head-piece at right angles to said axis; a holding sheave rotatably supported between said ears; ears extending downwardly from the head-piece and arranged in parallel planes at an angle 115 to the said axis said downwardly extending ears being directly beneath the upwardly extending ears; a closing block supported by said downwardly extending ears; a closing cable reaved about the sheaves of said 120 125 130

block; ears projecting laterally from the middle portion of the head-piece and substantially in line with said upwardly projecting ears; lead pulleys for the closing line supported between said laterally projecting ears; additional ears extending between and at right angles to said laterally projecting ears; and guide rollers for the

closing line supported by said last mentioned ears.

In testimony whereof, I hereunto affix my signature in the presence of two witnesses.

WILLIAM H. BOTTON.
